Attorneys

UNITED STATES PATENT OFFICE.

JOHN WARREN VEDDER, OF WORCESTER, MASSACHUSETTS.

STONE PRESS ROLL.

Application filed August 30, 1921. Serial No. 496,820.

To all whom it may concern:

Be it known that I, JOHN WARREN VEDDER, a citizen of the United States, and resident of Worcester, Massachusetts, have invented new and useful Improvements in Stone Press Rolls, which invention is fully set forth in the following specification.

This invention relates to rolls for paper making and especially to stone press-rolls by which the paper is pressed after it leaves the couch-rolls in paper making machines. Generally the object is to provide means, which may be effectively applied with facility and minimum effort, for mounting and securing the stone-body portion of stone-rolls upon the metal shaft thereof.

It has been heretofore proposed to employ at each end of the stone-body portion of a stone-roll a bushing closely fitting and making rotatable screw-threaded engagement with the metal shaft of the roll, said bushing being exteriorly tapered to fit the correspondingly flaring or countersunk outer end of the bore of the stone-body. In the use of such means the bushing must be rotated so that by its screw-threaded engagement with the shaft it will be moved along the latter into engagement with the stone-body. It has been found that the attainment of a tight fit with such means requires much effort and care because of the difficulty of rotating the bushing while its exterior surface is in contact with the opposing stone surface of the bore of the stone-body, the stone surface gripping the metal surface and opposing rotation of the bushing just as a piece of emery cloth gripped around the cylindrical surface of a piece of metal opposes rotation of the latter. Hence a further object of this invention is to provide a bushing adapted to be positioned tightly in place between the metal shaft and the stone-body with approximately no relative rotation of the two, but by movement of the bushing longitudinally of the shaft and stone-body.

A further object is the provision of a non-rotating bushing which by its movement longitudinally of the shaft in positioning the bushing will be caused to expand into tight engagement with the inner surface of the end of the bore of the stone-body portion of the roll; and this object is preferably attained by the cooperation of a tapered surface on the shaft with an interiorly tapered bore of the bushing, whereby as the bushing is moved longitudinally of the axis

of the shaft it will be caused to expand in the bore of the stone-body. A further object is the provision of a sleeve or ring in screw-threaded engagement with the shaft adapted to engage the end of the bushing in assisting in forcing the same to, and in securing it in, its final position. A still further object is the provision of a collar adapted to be screw-threaded on to said sleeve or ring after the latter has been put in place, said collar having an inner surface shaped to closely fit the end face of the stone-body, such arrangement permitting positioning of the collar in contact with the stone-body independently of the positioning of the bushing in engagement therewith.

The aforesaid and other objects and advantages are attained by the present invention, what I now regard as the preferred embodiment of which is illustrated in the accompanying drawing wherein—

Fig. 1 is a view partly in longitudinal section and partly in elevation, and

Figs. 2 and 3 are end and side elevations respectively of the expansible bushing such as interposed between the shaft and the stone-body at each end of the latter.

Referring to the drawing, 5 is the stone-body portion of the roll formed with an axial bore, a portion 6 of said bore at each end of the stone-body being preferably of slightly larger uniform diameter throughout than the middle section of the bore. A metal shaft 7, preferably tubular, extends through the bore of the stone body and projects at both ends to constitute bearings on the roll adapted to engage suitable supporting bearings not shown. Since the drawing illustrates similar means at both ends of the stone-body for mounting and securing the same upon the shaft, description of such means at one end of the roll only will suffice. Shaft 7 is formed with an exteriorly screw-threaded section or part 8 and adjacent thereto toward the middle of the shaft with a tapered section or part 9. 10 is a bushing of uniform exterior diameter normally slightly smaller than the interior diameter of the end section 6 of the bore of the stone-body portion 5, and having a tapering bore forming an interior surface conforming to the taper of the part 9 of the shaft. The bushing 10 is formed with three longitudinal slots spaced equidistant around and cut through the wall of the bushing, the slot 11 extending the full length of the bushing,

while the slot 12 extends from the left hand end to within a short distance of the right hand end of the bushing, and the slot 13 extends from the right hand end to within a short distance of the left hand end of the bushing. By such slotting the bushing is rendered expansible. 14 is a ring or sleeve interiorly screw-threaded for engagement with the threaded part 8 of the shaft, and also exteriorly screw-threaded for engagement by the interior screw-threads of a collar 15, the inner face of which is shaped to conform to the end surface of the stone-body with which it engages.

In assembling the parts the bushing 10 is first put in place by forcing it longitudinally along the tapered part 9 of the shaft until the resulting expansion of the bushing brings its exterior surface into tight engagement with the interior surface of the end portion 6 of the bore of the stone-body 5. Such longitudinal movement of bushing 10 may be effected by hammering, or by rotating collar 14 against the end of the bushing, or by both such methods, the collar 14 when set tightly against the end of the bushing also serving to secure the bushing in the desired position. It will be noted that in so positioning the bushing 10 no rotation thereof is required and I thus avoid the difficulty and effort experienced with bushings which must be rotated and in which the friction and gripping action between the opposing and contacting surfaces of stone-body and metal bushing must be overcome to bring the bushing to the desired position. A pin 16 may be employed to secure collar 14 against rotation after it has been tightly set against the end of the bushing. Collar 15 is next applied and rotated until its inner face is tightly set against the end surface of the stone-body. A pin 17 may be then put in place to lock the collar against rotation.

What I claim is:—

1. In a roll, the combination of a stone body having a central bore, a metal shaft extending through said bore and projecting at both ends of the stone body to constitute bearings on the roll for engagement with supporting bearings, and means securing said stone body upon said shaft said means including at one or both ends of the roll a bushing or sleeve on the shaft fitting in the end of the bore of the stone body member and having an exterior surface adapted to tightly engage the opposing surface of said bore and said bushing having an interior surface adapted to closely fit the opposing surface of the shaft member, the opposing surfaces of said bushing and of one of said members being correspondingly tapered and said bushing being movable longitudinally of the shaft without rotary movement relative to the stone body in bringing the bushing to its position between the shaft and

stone body, and means engaging the shaft and adapted to be brought into engagement with the end of the bushing without engaging the stone body to secure the bushing in place.

2. In a roll, the combination of a stone body having a central bore, a metal shaft extending through said bore and projecting at both ends of the stone body to constitute bearings on the roll for engagement with supporting bearings, and means securing said stone body upon said shaft said means including at one or both ends of the roll a bushing or sleeve on the shaft fitting in the end of the bore of the stone body member and having an exterior surface adapted to tightly engage the opposing surface of said bore and said bushing having an interior surface adapted to closely fit the opposing surface of the shaft member, the opposing surfaces of said bushing and of one of said members being correspondingly tapered and said bushing being movable longitudinally of the shaft without rotary movement relative to the stone body in bringing the bushing to its position between the shaft and stone body, and a ring screw-threaded on the shaft and adapted to be brought into engagement with the end of the bushing without engaging the stone body to secure the bushing in place.

3. In a roll, the combination of a stone body having a central bore, a metal shaft extending through said bore and projecting at both ends of the stone body to constitute bearings on the roll for engagement with supporting bearings, and means securing said stone body upon said shaft said means including at one or both ends of the roll an expansible bushing or sleeve on the shaft fitting in the end of the bore of the stone body member and having an exterior surface adapted to tightly engage the opposing surface of said bore and said bushing having an interior surface adapted to closely fit the opposing surface of the shaft member, the opposing surfaces of said bushing and of one of said members being correspondingly tapered and said bushing being movable longitudinally of the shaft without rotary movement relative to the stone body in bringing and expanding the bushing to its position between the shaft and stone body.

4. In a roll, the combination of a stone body having a central bore, a metal shaft extending through said bore and projecting at both ends of the stone body to constitute bearings on the roll for engagement with supporting bearings, and means securing said stone body upon said shaft said means including at one or both ends of the roll an expansible bushing or sleeve on the shaft fitting in the end of the bore of the stone body member and having an exterior surface adapted to tightly engage the oppos-

- ing surface of said bore and said bushing having an interiorly tapered surface adapted to fit and cooperate with a correspondingly tapered surface on the shaft whereby 5 said bushing by longitudinal non-rotary movement relative to the stone body may be moved and expanded to its position between the shaft and stone body.
5. In a roll, the combination of a stone 10 body having a central bore, a metal shaft extending through said bore and projecting at both ends of the stone body to constitute bearings on the roll for engagement with supporting bearings, and means securing 15 said stone body upon said shaft said means including at one or both ends of the roll an expansible bushing or sleeve on the shaft fitting in the end of the bore of the stone body member and having an exterior surface of approximately uniform diameter 20 throughout adapted to tightly engage a corresponding opposing surface of said bore and said bushing having an interiorly tapered surface adapted to fit and cooperate 25 with a correspondingly tapered surface on the shaft whereby said bushing by longitudinal non-rotary movement relative to the stone body may be moved and expanded to its position between the shaft and the stone 30 body.
6. In a roll, the combination of a stone body having a central bore, a metal shaft extending through said bore and projecting at both ends of the stone body to constitute 35 bearings on the roll for engagement with supporting bearings, and means securing said stone body upon said shaft said means including at one or both ends of the roll an expansible bushing or sleeve on 40 the shaft fitting in the end of the bore of the stone body member and having an exterior surface adapted to tightly engage the opposing surface of said bore and said bushing having an interiorly tapered surface 45 adapted to fit and cooperate with a correspondingly tapered surface on the shaft whereby said bushing by longitudinal non-rotary movement relative to the stone body may be moved and expanded to its
- position between the shaft and stone body, 50 and a ring screw-threaded on the shaft and adapted to be brought into engagement with the end of the bushing without engaging the stone body to secure the bushing in place. 55
7. In a roll, the combination of a stone body having a central bore, a metal shaft extending through said bore and projecting at both ends of the stone body to constitute 60 bearings on the roll for engagement with supporting bearings, and means securing said stone body upon said shaft said means including at one or both ends of the roll an expansible bushing or sleeve on the shaft fitting in the end of the bore of the stone 65 body member and having an exterior surface adapted to tightly engage the opposing surface of said bore and said bushing having an interiorly tapered surface adapted to fit and cooperate with a correspondingly tapered surface on the shaft whereby 70 said bushing by longitudinal non-rotary movement relative to the stone body may be moved and expanded to its position between the shaft and stone body, a ring screw-threaded on the shaft and adapted to be brought into engagement with the end of the bushing without engaging the stone body to secure the bushing in place, and a collar 75 making screw-threaded engagement with the exterior surface of said ring and adapted to engage the end surface of said stone body.
8. In a roll, the combination of a stone body having a central bore, a shaft extending 80 through said bore, an expansible bushing surrounding the shaft and adapted to be positioned in the end of the bore of the stone body, and means acting upon longitudinal movement of the bushing relative to 85 the shaft and stone body and without rotary movement of the bushing to expand the same 90 into tight engagement with the surrounding wall of the bore of the stone body.

In testimony whereof I have signed this 95 specification.

JOHN WARREN VEDDER.
